UNITED STATES PATENT OFFICE.

PAUL EUGÈNE SILLIÈRE, OF NEW YORK, N. Y., ASSIGNOR TO GARNER PRINT WORKS & BLEACHERY, OF NEW YORK, N. Y., A CORPORATION OF NEW YORK.

DESIGN FOR PIECE GOODS.

Application filed October 17, 1922. Serial No. 4,004. Term of patent 7 years.

To all whom it may concern:

Be it known that I, PAUL E. SILLIÈRE, a citizen of the United States, residing in the city of New York, borough of Manhattan, in the county and State of New York, United States of America, have invented a new, original, and ornamental Design for Piece Goods, of which the following is a specification, reference being had to the accompanying drawing, forming a part thereof.

The figure represents a plan view of my design as particularly adapted to a cretonne.

The design consists essentially of a rose arbor trellis effect so arranged as to form vistas in which are located representations of birds in flight.

What I claim, and desire to secure by Letters Patent is:

The ornamental design for piece goods, substantially as shown and described.

PAUL EUGÈNE SILLIÈRE.
